1

This invention relates to coin boxes for use in telephone or like installations.

The object of the invention is to provide an improved construction of coin-insertion and delivery mechanism and improved means for preventing fraud.

In accordance with this invention, a coin box in which a coin platform is arranged to occupy three possible positions viz. a refunding position in which inserted coins are returned to the user, a neutral position in which the coins are retained on the platform, and a collection position in which the coins are passed to a fee-containment, and in which the coin platform is moved to the refund position upon hanging up the receiver, is characterised in that when the receiver hook is raised, the coin platform is put under the exclusive control of a mechanism which is arranged to be necessarily actuated during the insertion of the coin or coins, whereby the coin platform is moved into its neutral position during the coin-inserting movement.

In order that the invention may be clearly understood, a description will now be given of one of its embodiments, reference being made for this purpose to the accompanying drawings, in which:

Fig. 1 is a perspective view of a coin box mechanism in accordance with the invention;

Fig. 1 (a) is a perspective view of a portion of the coin box mechanism.

Fig. 2 is a side elevation of the same with parts omitted for clarity showing, in full lines the rest and refund position, and in broken lines the condition when the telephone receiver has been lifted;

Fig. 3 is a similar view showing, in full lines the condition when, the receiver being off its hook, a coin has been inserted and the coin slide allowed to return to normal, and in broken lines the condition with the coin slide depressed; while

Fig. 4 is a similar view showing the collection position resulting from an electrical signal over the lines.

As shown in the drawings, the mechanism comprises two side plates 1 and 2 which carry the mechanism and between which is arranged an oscillating coin-platform 3. Fixed horizontally between the two side plates is a cover 5 provided with two rollers 4, one at the front and one at the back, and also with a central opening which serves for the reception of the coins. Also fixed between the two supports 1 and 2 are two plates 6, one behind the horizontal plate and the other

in front of it, lying below the level of the horizontal plate and inclined up towards it. Each of these carries a roller 7 at its upper end, so that there is a narrow slit formed between each of the pairs of rollers 4 and 7. The platform 3 can take three positions, viz. two in which it is held between one pair of rollers only and the other in which it is held between both pairs, the first two being inclined and the other horizontal. These two inclined positions serve, as will be described, one for collecting the money and the other for returning it.

A projection on the rear side of the coin slide (not shown) acts on a cranked lever 8, rotatable freely on a pivot 9 which is fixed in the plate 1 and in the support 10. A link 11 connects the lever 8 to another lever 12 which is fixed to the end of a shaft 13 freely journaled in the supports 1 and 2. As the coin slide is depressed, clockwise movement of the crank lever 8 and shaft 13 occurs against the force of a tension spring 14, which serves to bring these parts back to their rest positions as soon as the coin slide is released, the rest positions being determined by the engagement of the lever 12 with a stop 15 fixed to the support 10.

The other end of the shaft 13 carries freely a lever 16 for locking the switch hook of the telephone set; this lever 16 resting, under the influence of a spring 17, on a bent part 18 of an intermediate piece 19 fixed on the shaft 13. When said shaft 13 rotates, a finger 20 on the intermediate piece 19 engages a lever 21 resting normally against a lever 22 under the influence of a coil spring 23 which tends to bring the two together. Another coil spring 24 is fixed at one end to a fixed stop 25, and at the other end to the lever 21, so that 21 is drawn up against 22, and 22 in its turn against the stop 25. Rotatable about a pivot 26 is a retaining pawl 27 which under the action of a spring 28 rests against a stop 29 riveted on the lever 22 and which serves to restrain the lever 22 when it reaches the end of that part of its movement necessary for putting the oscillating platform 3 into its horizontal position. The platform 3 is mechanically connected to the lever 22 by means of a link 30, which is carried at one end on a pivot 31 riveted on the lever 22 and at the other end on a pivot 32 riveted to a sector-shaped piece 33 fixed on a shaft 34. This sector-shaped piece 33 in its turn supports a plate 35 rigidly fixed thereto. It results from this arrangement that the displacement of the lever 22 causes rotation of the shaft 34 and of the sector 33 and the plate 35. The plate 35

carries at its extremity a spindle 36 upon which the platform 3 is freely pivoted. Thus the platform can make two movements simultaneously, viz. one about the axis 34 and the other about the axis 36. When the lever 21 is moved forwardly and downwardly, a lug 37 on its extremity can hook behind the nose of a retaining pawl 39 which normally rests against a stop 40 under the influence of a spring 41. At the same time a retaining pawl 42 abutting against a pivot 43 riveted on the lever 21, latches with its nose 44 underneath a member 45.

In Fig. 2 there is shown the cashing-in magnet 46 and the toothed sector 47 of the receiver hook, the latter including a toothed arcuate portion 47' which is engageable by the lug 48 on the lever 16 when the latter is turned downwardly.

DESCRIPTION OF THE OPERATION

When the apparatus is at rest, the receiver being on its hook and the coin slide and crank 8 in their upper positions, the parts are situated as shown in full lines in Fig. 2, the coin-platform being in its refund position supported between the left-hand pair of rollers 4 and 7.

When the receiver is lifted off its hook, the member 41 swings into the dash-line position of Fig. 2, allowing the pawl 39 to drop under the force of its spring 41 into operative position.

As the money is being inserted, this action involving depression of the coin slide (not shown), the cranked lever 8 is turned downwardly to the position shown in dash lines in Fig. 3, and this movement of the lever 8 is transmitted through the shaft 13 to the intermediate piece 19 of which the finger 20 at the commencement of its movement actuates the lever 21. Under the force of the spring 23 the lever 21 takes with it the lever 22 until the latter is stopped by the pawl 27 engaging the stud 29 thereon. The lever 21 continues its movement, thus loading the spring 23 and further loading the spring 24, and is caught and held by the engagement of the hooked part 37 on the lever with the retaining pawl 39, during the releasing movement of the coin slide after it has been to the bottom. The clockwise movement of lever 22 is transmitted through the intermediary of link 30, the sector 33 and the plate 35, to the platform 3, which is thus brought into a horizontal position. At this moment the lever 22 is retained by the pawl 27. In this position the platform, closing the opening in the plate 5, catches the coin which falls a few moments later. During the downward movement of the coin slide the crooked part 43 of the pawl 16 engages in one of the gaps in the toothed sector 47 of the received hook mechanism, and only frees it when the slide is released a little before reaching its upper or rest position. With the coin inserted, and the coin slide released, the parts are as shown in full line in Fig. 3.

Two possibilities must now be envisaged:

(1) Money refund

If the receiver is replaced on its hook before a call is made the toothed sector 47 is returned to the full line position of Fig. 2, where it is in engagement by means of a bent-up part 49 with the extremity of pawl 39. Thus the lever 21 is freed, and under the action of the springs 23 and 24 it snaps backward, hitting against the lever 22, and carrying it back, now under the influence of spring 24 alone, into the rest position. As the lever 22 is connected mechanically with the platform 3, this platform also is shifted back into the

position of Fig. 2 where the lever is stopped by the abutment 25. In the meantime the coin, which is no longer held on the platform, falls through an appropriate chute (not shown) into a tray from which the user can recover it. The mechanism is now in the original "rest and refund" position of Fig. 2.

(2) Collection

After the establishment of a telephone connection an energising current is fed to the magnet 46 and operates it, so that through the intermediary of a lever 50 it acts on the pawl 27 to unhook the nose portion 51 from the pivot 29 on the lever 22. Accordingly, under the force of spring 23, the lever 22 impinges by its lug 52 against the nose 38 of the pawl 39, raising it and disengaging the lug 37 on the lever 21, finally engaging the lever 21. During this abrupt movement the lever 22 carries with it the platform 3, and the parts are finally disposed as shown in Fig. 4, the money falling into an appropriate receptacle (not shown).

During the attraction of the armature of the electromagnet, the lever 50 which actuates the pawl 27, acts at the same time on the pawl 42, but immediately the magnet is released the lever 50 liberates the two pawls 47 and 42. The latter disengages from the member 45 under the action of spring 41, thus freeing the mechanism which returns with a snap to the rest position of Fig. 2 under the influence of spring 24, the platform 3 passing through the horizontal or neutral position.

ATTEMPTED FRAUDULENT USES

Below are given the conditions of functioning in case of improper manipulation:

(1) Manipulation of the receiver hook when the money slide is at the bottom of its travel.

By inserting a piece of money into the coin box, an impulsing mechanism is prepared, and it is only upon release of the slide that the impulse distinctive of the money is transmitted. If the slide were held down, supposing that one would be able to operate the toothed sector 47, it is conceivable that the user could recover his money by means of the receiver hook. This maneuver would open the coin-receptacle; but the latter could be closed again by depressing the switch hook after releasing the money into the refund chute. If at this moment the slide were released, the money identification impulse would be sent and the connection made without being paid for.

In order to prevent this, it is sufficient to block the toothed sector 47 at the commencement of the depression of the money slide. This is effected by means of a lever 16 of which a lug 48 engages in the gaps between the teeth of the sector so that it cannot be displaced, and in consequence the lug 49 on the sector cannot be made to act on the pawl 39 to shift it into the "refund" position until after the money slide has returned to its upper or rest position, that is until after the sending of the identification impulse.

(2) Possibility of collection with the slide held down.

The position of the slide must not in any way affect the collection of the money, otherwise one would be able to establish a communication after having introduced the required fee together with a supplementary piece with which one could hold the slide down in such a way that the collection could not take place. After communica-

tion the money would be recovered. Measures must be taken to prevent this fraud.

To this end the construction is such that the lever 22 which controls the platform 3 turns freely on the shaft 13 which is controlled by the coin slide through the intermediary of the cranked lever 8. From this it results that the lever 22 is quite independent of the position of the slide, so that when the collection magnet is operated, the lever 22 falls abruptly against the lever 21, at the same time moving the platform into the collection position.

Having now particularly described and ascertained the nature of our said invention and in what manner the same is to be performed, we declare that what we claim is:

1. A telephone coin box comprising a coin platform pivotally movable into three positions of operation, a normal first position for refunding coins inserted in said box, a second position for retaining coins on said platform, a third position for collecting coins deposited in said box, receiver hook means operative to move said platform from said second to said first position upon replacing the receiver before completion of a call, coin actuated means controlled by said hook means being operative to move said platform from said normal first position into said second position and retaining means connected to said coin actuated means for limiting the operation of said receiver hook when said coin means are actuated.

2. A telephone coin box comprising a coin platform movable into three positions, a first normal position for refunding coins inserted in the box, a second position for retaining coins on said platform, a third position for collecting coins in a coin receptacle, call connection responsive means, platform positioning mechanism operable to move said platform from said second position through said third position and from said second position to said first normal position in response to operation of said call connection responsive means independently of operation of the receiver hook, coin actuated means controlled by the deposit in the box of a proper coin for moving said platform into said second position whereby coins inserted into said coin box will be retained on the platform and retaining means connected to said coin actuated means, operative to prevent operation of a receiver hook when said coin means is actuated.

3. A telephone coin box as set forth in claim 1 wherein said means for preventing the operation of said receiver hook comprises a lever having a catch formed integral therewith, said catch being operatively positioned to engage said receiver hook in one position of operation.

4. A telephone coin box comprising a coin platform movable into three positions, a first normal position for refunding coins inserted in the box, a second position for retaining coins on said platform, a third position for collecting coins in a coin receptacle, call connection responsive means, platform positioning mechanism operable to move said platform from said second position through said third position and said second position to said first normal position in response to operation of said call connection responsive means independently of operation of the receiver hook, and coin actuated means controlled by the deposit in the box of a proper coin for moving said platform into said second position whereby coins inserted into said coin box will be retained on the platform.

5. A telephone coin box comprising a coin platform movable into three positions, a first position for refunding coins inserted in the box, a second position for retaining coins on said platform, a third position for collecting coins in a coin receptacle, coin actuated platform positioning means adapted to move said platform from said first position to said second position upon the insertion of a coin, and means under the control of the receiver hook for rendering said platform positioning means ineffective when the receiver is supported on the receiver hook.

6. A telephone coin box comprising a coin platform movable into three positions, a first position for refunding coins inserted in the box, a second position for retaining coins on said platform, a third position for collecting coins in a coin receptacle, coin actuated platform positioning means adapted to move said platform from said first position to said second position upon the insertion of a coin in the box, comprising a shaft rotated in response to the insertion of a coin in the box, a pivotally mounted lever rotated with said shaft, a second lever, resilient connecting means interconnecting said first and second levers whereby movement of said first lever will cause movement of said second lever through said resilient means, and mechanical linkage means interconnecting said second lever and said platform.

7. Telephone coin box in accordance with claim 6 including stop means for said second lever limiting the travel thereof to a position wherein said platform is in said second position while permitting further movement of said first lever to tension said resilient connecting means.

8. Telephone coin box in accordance with claim 7 and further comprises actuating means operated upon the completion of a call, said actuating means being adapted to release said second lever stop means thereby permitting said second lever to move against said first lever by the action of said tensioned resilient connecting means thereby moving said platform from said second coin retaining position to said third coin collection position.

9. Telephone coin box in accordance with claim 8 and further comprises resilient means interconnecting said first lever and a stationary point, said last named resilient means being tensioned upon said first lever being rotated by said shaft and adopted to return said first and second levers upon release of said actuating means.

10. Telephone coin box in accordance with claim 6 in which said first and second levers are freely rotatably mounted in said shaft, said shaft including means secured thereto for engaging said first lever upon rotation in one direction of said shaft to compel movement thereof in the same direction but permitting rotation of said shaft in the opposite direction independently of said shaft.

11. A telephone coin box comprising a coin platform movable into three positions, a first position for refunding coins inserted in the box, a second position for retaining coins on said platform, a third position for collecting coins in a coin receptacle, coin actuated platform positioning means including means for moving said platform from said normal first position to said second position upon the insertion of a coin, locking means for retaining said platform in said second position, a spring opposing said movement and tensioned thereby, receiver hook means

adapted to release said locking means upon replacement of said receiver prior to completion of a connection to permit movement of said platform from said second position to said first position by the action of said tensioned spring.

12. A telephone coin box comprising a coin platform movable into three positions, a first position for refunding coins inserted in the box, a second position for retaining coins on said platform, a third position for collecting coins in a coin receptacle, coin actuated platform positioning means including means for moving said platform from said first position to said second position, a return spring opposing such platform movement and tensioned thereby, locking means for retaining said platform in said second position against the tension of said spring, a collection magnet, an armature for said magnet, operatively associated with said platform means and under the control of said armature for moving said platform from said second position to said third position and adapted to release said locking means upon energization of said collection magnet, said tensioned return spring being adapted to return said platform from said

10
15

third position through said second position to said first position upon deenergization of said collection magnet.
